US0D1092446S

(12) **United States Design Patent** (10) **Patent No.:** **US D1,092,446 S**
(45) **Date of Patent:** **** Sep. 9, 2025**

(54) **EARPHONE**

(71) Applicant: **SONY GROUP CORPORATION**,
Tokyo (JP)

(72) Inventor: **Naoki Sugiyama**, Tokyo (JP)

(73) Assignee: **SONY GROUP CORPORATION**,
Tokyo (JP)

(**) Term: **15 Years**

(21) Appl. No.: **29/912,774**

(22) Filed: **Sep. 22, 2023**

(30) **Foreign Application Priority Data**

Mar. 22, 2023 (JP) ..... 2023-005566 D

(51) **LOC (15) Cl.** **14-01**

(52) **U.S. Cl.**

USPC **D14/223**

(58) **Field of Classification Search**

Friedrich LLP

(57) **CLAIM**

The ornamental design for an earphone as shown and described.

DESCRIPTION

FIG. 1 is a front, left perspective view of an earphone showing my new design;

FIG. 2 is a front, right perspective view thereof;

FIG. 3 is a rear, right perspective view thereof;

FIG. 4 is a front elevational view thereof;

FIG. 5 is a rear elevational view thereof.

FIG. 6 is a left side elevational view thereof; and

FIG. 7 is a right side elevational view thereof;

FIG. 8 is a top plan view thereof; and

FIG. 9 is a bottom plan view thereof; and,

FIG. 10 is a partially enlarged front elevational view thereof along the lines 10-10 and 10'-10' of FIG. 4.

The broken lines illustrating portions of the earphone form no part of the claimed design.

1 Claim, 10 Drawing Sheets
